ILLUMINABLE CHRISTMAS TREE STAND
OR SIMILAR ARTICLE

Anthony Shales, 474 County Line Road,
Huntingdon Valley, Pa.

Filed July 22, 1963, Ser. No. 75,910

Term of patent 3½ years

(Cl. D35—3)

FIG. 1

FIG. 2

FIG. 3

FIGURE 1 is a plan view of an illuminable Christmas tree stand or similar article showing my design;

FIGURE 2 is an elevational view thereof; and

FIGURE 3 is a view taken on line 3—3 of FIGURE 2.

I claim:

The ornamental design for an illuminable Christmas tree stand or similar article, as shown.
